UNITED STATES PATENT OFFICE.

GUSTAVE KOCH, OF NEW YORK, N. Y.

BOTTLE-STOPPER.

SPECIFICATION forming part of Letters Patent No. 595,814, dated December 21, 1897.

Application filed February 1, 1897. Serial No. 621,525. (No model.)

To all whom it may concern:

Be it known that I, GUSTAVE KOCH, a subject of the Emperor of Germany, and a resident of New York, county and State of New 5 York, have invented a certain new and useful Improvement in Bottle-Stoppers, of which the following is a full, clear, and exact specification.

My invention relates to bottles and bottle-stoppers; and it consists of a stopper comprising a plug of hard material adapted to be inserted in the neck of a bottle, an elastic packing secured to the plug, a longitudinal slot axially through the plug, segmental slots 15 on opposite sides of the slot in the head of the plug, a band rotatably secured to the neck of the bottle, and a bow pivotally secured to the band and adapted to lock the stopper in the neck of the bottle.

20 My invention further consists in the peculiar construction of the packing and in the mode of its attachment to the plug, whereby the packing, besides serving for hermetically closing the space between the walls of the neck 25 of the bottle on the body of the plug, is also utilized as a spring for the purpose of ejecting the plug when the pressure holding it in the neck of the bottle is released.

My invention is illustrated in the accompanying drawings, wherein—

Figure 1 is an elevation, partly a section, showing my improved bottle-stopper in the mouth of the bottle and secured in this position. Fig. 2 is a side view of Fig. 1. Fig. 3 35 is an elevation at a right angle to Fig. 1, showing my improved bottle-stopper set in the mouth of the bottle, but not locked. Fig. 4 is a similar elevation showing the bottle-stopper removed from the mouth of the bottle. Fig. 40 5 is a horizontal section on line 5 of Fig. 2. Fig. 6 is a horizontal section on line 6 of Fig. 3, and Fig. 7 is a bottom view of the elastic packing.

Similar letters of reference indicate corresponding parts in all the views of the drawings.

50 Plug *a*, preferably produced of porcelain or some similar substance in the shape shown in the drawings, is concavely tapered from the head toward its flanged end. Slightly above this end a groove *b* is provided in the body of

the plug, adapted to receive the flange *b'* of the elastic packing *c*.

The packing is made of elastic material, preferably of rubber, and besides serving the purpose of hermetically closing the mouth of the bottle when the stopper is inserted the peculiar arrangement of the flange *b'*, held in the groove *b* of the stopper, will cause it to rebound when the pressure forcing the stopper in the mouth of the bottle is released, and thereby to eject the stopper from the mouth of the bottle.

The normal position of the packing on the body of the plug is shown in Fig. 3. Flange *b'* is then on the level of the upper surface of the ring. When, however, the plug is pressed into the mouth of the bottle, the position of the ring in relation to the flange *b'* is reversed, the ring being then turned upward. When 70 the pressure is released, the packing strives to regain its normal position, the flange *b'*, stretched under pressure, contracts, and the ring *c*, returning to its position, lifts the stopper from the mouth of the bottle.

The locking of the stopper in the mouth of the bottle is accomplished by the bow *d*, which is pivotally connected to the band *e*, fitted turnably on the neck of the bottle in the recess underneath its head.

In the body of the plug is provided a longitudinal slot *f*, parallel with the axis of the plug, extending from its head to about the middle of its body, and in connection therewith are provided the slots *f'* and *f''*, forming 85 segmental shoulders *g* and *g'*, situated on its opposite edges. The shape and relative position of these segmental shoulders are shown in the sectional view, Fig. 6, and in the similar view, Fig. 5, is shown how the plug is 90 locked in the neck of the bottle by the bow *d*, turned over these shoulders into the slots *f* and *f''*, respectively.

Band *e* is made of a flat strip of metal, and bow *d* preferably of spring-wire, and they have 95 also the function of attaching the stopper permanently to the bottle, as shown in Fig. 4, when the same is removed from its mouth.

The operation of closing a bottle with my improved bottle-stopper and of removing it 100 again is very simple and suggests itself from the foregoing description.

The stoppers permanently attached to the bottles are normally in the position shown in Fig. 4. To close the bottle, the operator sets the stopper in the position shown in Fig. 3 and 5 presses it into the mouth of the bottle until the bow *d* reaches the top of slot *f*. He then gives the bow a turn to the right by applying the thumb and middle finger to the projecting parts *t* and *t'* of the bow *d*, so that the 10 bridge *d'* will slide upon the shoulders *g* and *g'*. The stopper will then be securely locked in the neck of the bottle. To open the bottle and to remove the stopper from its mouth, it is only necessary to turn the bow *d* back, 15 bringing bridge *d'* in parallel position with the slot *f*, whereupon the rebounding of the elastic packing will eject the stopper from the mouth of the bottle.

I claim as my invention and desire to set 20 cure by Letters Patent—

1. A stopper for hermetically closing the mouth of a bottle or similar vessel, comprising a conically-shaped plug, concavely tapering toward its flanged end and provided with 25 a groove near its lower flanged end, an elastic packing-ring, having a flange on its inner periphery, secured in the groove, a longitudinal slot in the body of the plug, horizontal slots in the head of the plug connecting with 30 the vertical slot and forming segmental shoulders, a band rotatably secured on the neck of the bottle and a bow, pivotally secured to the band and passing through the slot of the plug.

2. In a bottle-stopper for hermetically closing the neck of a bottle or similar vessel, the 35 combination with a conical plug concavely ta-

pered toward its flanged end, and having a vertical slot through its top, segmental slots communicating with the vertical slot and forming shoulders on the opposite upper edges thereof, a groove near its flanged end, and with an elastic packing, slid on the body of the plug and secured by its flange in the groove, of a band, set turnably on the neck of the bottle and of a bow, pivotally secured to the band 45 and passing through the vertical slot of the stopper, and adapted to be slid on the segmental shoulders thereof for the purpose of locking the stopper in the mouth of the bottle.

3. In a stopper for hermetically closing the 50 neck of a bottle or similar vessel, the combination with a conically-shaped plug, concavely tapered toward its flanged end and having a groove, adapted to receive and hold the flanged rim of a packing, of an elastic 55 packing-ring, circular in section having a flange around its inner periphery on the level with its upper surface, the packing-ring being secured by this flange in the groove in the body of the plug in such position, that 60 when the stopper is pressed inward into the neck of a bottle, the flange is drawn and reacts as a spring when the pressure upon the plug is released.

In witness that I claim the improvements 65 described in the foregoing specification I have signed my name in the presence of two subscribing witnesses.

GUSTAVE KOCH.
